UNITED STATES PATENT OFFICE

ERNST PAUL LEHMANN AND KARL RUPPIN, OF BRANDENBURG-ON-THE-HAVAL, GERMANY, ASSIGNORS TO SAID LEHMANN

TOY

Application filed February 7, 1928, Serial No. 252,619, and in Germany January 23, 1928.

Toys are known, in which articles capable of rotating, such as balls or coins, can be put into continuous motion on a support to be held in a horizontal position. There are also 5 similar toys, in which a rotatable disc is provided, on which the articles in question are put in motion by mechanical means.

In contradistinction to the toys referred to, the present invention has for its object to 10 arrange a rotatable disc in such a manner that it can be held freely in the hand approximately horizontally and, after the article (ball or the like) to be given a rotary motion has been placed on it, can be rotated about a 15 vertical axis directly by the other hand or by clockwork, the coaction of the two operations causing the suitably shaped articles which are to be placed on the disc (by suitably changing the position of the approxi- 20 mately horizontally freely held plate) to be moved in such a manner that they remain continuously upright while rolling and running in a circle, without falling off the disc.

In the accompanying drawing three con- 25 structional examples of the invention are shown diagrammatically, Figs. 1 and 2 being a side elevation and plan view of one constructional form, Figs. 3 and 4 a vertical section through another constructional form 30 and a plan view thereof and Figs. 5 and 6 a vertical section and plan view of a third constructional form.

1 is the rotatable disc or plate, which in Figs. 1 and 2 is quite flat, in Figs. 3 and 4 is 35 slightly raised towards the edge and in Figs. 5 and 6 has a more decidedly upturned edge. 2 is a shaft supporting the disc at 3. 4 is a handle in which the shaft lies loosely. This handle has a wider portion 5 at its upper end 40 for preventing the disc, which rotates above the widened portion with only a slight clearance 6, from bending. Should the disc become bent, it will slide on the upper surface of the widened portion 5 of the handle 45 without being able to become more bent and get out of true, so that the object of the toy can always be attained.

In the constructional form shown in Fig. 3 in the middle part of the lower surface of 50 the disc 1 is a reinforcement 7 for preventing

the shaft 2 which is attached at 3 from becoming bent at this point. With the same object in view the upper end of the handle part 4 is again widened by the provision of a fixed dish or plate 8 which is open to the top and between which and the disc 1 there is normally a slight clearance 6.

In the example shown in Figs. 5 and 6 the disc 1 has a rim 9 which has a decided upward bend. Such an upwardly bent rim is 60 not actually required for carrying out the object of the toy, but it is of advantage to less expert players if, where there is a certain lack of skill, the ball, coin or the like is prevented by such a rim from rolling off the 65 plate. In this example the drive is not operated entirely by hand but by means of a spring or clockwork mechanism 10 of any suitable kind, which can be wound up by the key or fixed handle 11. Thus, while the hand 70 holding the handle is occupied, the other hand remains free, while the disc is being turned by the clockwork, for more easily placing the ball, coin or ring on the rotary disc after it has commenced to rotate, which 75 requires a certain amount of skill.

In Figs. 1 and 3, on the other hand, a crank 12 is provided for turning the shaft 2 and with it the disc 1. In the example shown in Fig. 3, toothed gearing 13 is provided, for 80 enabling both the speed of rotation of the disc to be varied and the drive to be effected at right angles to the shaft 2 from the side instead of from below. 14, 15 and 16 are 85 examples of articles to be laid on the disc and to be caused to rotate thereon, the article in Figs. 1 and 2 being a disc or coin, in Figs. 3 and 4 a ball, and in Figs. 5 and 6 a ring, more particularly a rubber ring.

What we claim is:

1. A toy for playing a game of skill, comprising in combination a vertical handle, having its upper end of greater diameter than the handle, a shaft extending axially through said handle and capable of rotating loosely 95 therein, means carried by said shaft capable of being actuated by one hand for rotating the shaft continuously in the same direction while the handle is held substantially stationary with the other hand, and a rotatable 100

disc or plate mounted on the top end of the shaft, on which articles capable of rolling can be placed, when the disc is rotating, for imparting a continuous rotary motion to them, the top surface of the enlargement at the upper end of the handle being almost but not quite in contact with the under surface of the rotatable disc all round a circumference equal to at least half that of the said disc, as set forth.

2. A toy for playing a game of skill, comprising in combination a vertical handle, a shaft extending axially through said handle and capable of rotating loosely therein, means carried by said shaft capable of being actuated by one hand for rotating the shaft continuously in the same direction while the handle is held substantially stationary with the other hand, a rotatable disc or plate mounted on the top end of the shaft, on which articles capable of rolling can be placed, when the disc is rotating, for imparting a continuous rotary motion to them, and a dished plate having its concave side uppermost fixed to the top end of the handle for preventing the rotary disc from becoming bent, as set forth.

In testimony whereof we have signed our names to this specification.
